BENJAMIN ILLINGWORTH, OF FREEPORT, ILLINOIS, ASSIGNOR TO ANDREW J. BRUBAKER AND ALBERT BLISS, JR.

Letters Patent No. 73,895, dated January 28, 1868.

IMPROVEMENT IN CHURNS.

The Schedule referred to in these Letters Patent and making part of the same.

TO ALL WHOM IT MAY CONCERN:

Be it known that I, BENJAMIN ILLINGWORTH, of Freeport, in the county of Stephenson, and in the State of Illinois, have invented certain new and useful Improvements in Churns; and do hereby declare that the following is a full, clear, and exact description thereof, reference being had to the accompanying drawings, and to the letters of reference marked thereon.

In the annexed drawings, making part of this specification, A represents a churn-dasher, constructed substantially in the form represented, being provided on its upper side with two annular grooves or recesses, E and F, from the bottoms of which are made the holes d d and a a. B represents the churn-staff, the lower end of which is made fast to the dasher A. This staff is made hollow from one end to the other. In the upper end of the hollow of the shaft is inserted a plug, D, over the lower end of which plug is first drawn an India-rubber nipple, C. This nipple has a slot in its lower end. The plug is made hollow, so that in churning, as the dasher and staff rise, air is drawn in the churn through the plug and through the slot in the nipple, and then through the hollow shaft. When the dasher and staff descend, the slot in the nipple closes, to prevent the passage of air backwards, or up and out of the staff.

This arrangement is for the purpose of introducing air into the churn during the process of churning butter, to facilitate the operation.

Having thus fully described my invention, what I claim as new, and desire to secure by Letters Patent, is— The dasher A, as constructed, used with the staff B, made hollow, and provided with the plug D and nipple C; substantially as and for the purpose set forth.

In testimony that I claim the foregoing, I have hereunto set my hand, this 2d day of July, 1867.
